UNITED STATES PATENT OFFICE.

PERCY DOUGLAS IVEY, OF GUELPH, AND ALFRED JAMES SALISBURY, OF TORONTO,
ONTARIO, CANADA.

STORAGE BATTERY.

1,340,269.

Specification of Letters Patent. Patented May 18, 1920.

Application filed February 14, 1919. Serial No. 277,036.

To all whom it may concern:

Be it known that we, **PERCY DOUGLAS IVEY**, of the city of Guelph, in the county of Wellington, in the Province of Ontario, Canada, and **ALFRED JAMES SALISBURY**, of the city of Toronto, in the county of York, in the Province of Ontario, Canada, have invented certain new and useful Improvements in Storage Batteries, of which the following is the specification.

Our invention relates to improvements in storage batteries and the object of the invention is to devise means in a storage battery not liable to get out of order or fail to work, which will always clearly indicate the density of the electrolyte during the use of the battery so that the owner will have instantaneously and without close inspection a definite indication as to the condition of the electrolyte and when the cell is in need of recharging and it consists essentially of the arrangement and construction of parts as hereinafter more particularly explained.

Figure 1, is a vertical sectional view showing an alternative construction.

Fig. 2, is a plan view of the construction shown in Fig. 1.

In the drawings like letters of reference indicate corresponding parts in the various figures.

7 indicates the wall of the battery which is divided by partitions 8 and 9 into cells 10, 11 and 12. Spaced from the wall 7^a of the cell and extending between the dividing walls 8 and 9 are cross walls 13, which extend down at their lower ends in proximity to the bottom of the cell but do not touch such bottom, leaving an intervening opening for the passage of the fluid contained in the cell.

The space between the cross walls 13 and the wall 7^a of the battery is divided by vertical strips 15 and 16 extending between the cross wall 13 and the wall of the battery thereby forming chambers 17, 18 and 19 in each cell, each chamber filling with fluid to the same level as the fluid in the battery.

Each space 17, 18 and 19 is provided with a buoyant element 20, these buoyant elements varying in specific gravity so as to indicate a reading.

The reading of the different beads, of course, depends upon the density, and as the beads are located in separate vertical chambers the reading is thereby facilitated as each bead stands out separate and distinct from the other and thereby different densities of the electrolyte are readily distinguishable.

In former constructions adopted the beads have been always located in the same vertical passage-way or chamber, the effect being in many cases that the beads indicating different densities would sometimes 65 jam in the passage-way, and, therefore the reading frequently could not be depended upon. By having a bead for each density in a separate passage-way this difficulty is 70 entirely overcome, and a correct reading is 75 always assured.

Another advantage, which we obtain in our construction resides in the fact that should one of the beads be defective in construction such as would cause it to leak or crack during use it would not render inoperative the other beads. This defect is likewise obviated by the construction, which we have heretofore described.

What we claim as our invention is:

In a battery cell having transparent walls, a supplemental wall located in proximity to one of the walls and provided with partitions extending between it and the wall whereby separate chambers are provided, 85 the said chambers communicating with the main cell, whereby the electrolyte is common to all, each chamber being provided with a single bead or buoyant element in the electrolyte, whereby the reading and free 90 movement of each bead is facilitated.

PERCY DOUGLAS IVEY.
ALFRED JAMES SALISBURY.
